[57] CLAIM

The ornamental design for a cage for the support rollers of a sliding window or similar article, as shown.

DESCRIPTION

FIG. 1 is a perspective view of a cage for the support rollers of a sliding window or similar article showing my new design, looking toward one side and end thereof; and

FIG. 2 is a perspective view thereof looking toward the same side and opposite end thereof.

The opposite side is a mirror image of the one side. The interior of the article is plain.
